UNITED STATES PATENT OFFICE.

JAMES M. RECTOR, OF ELK PARK, MONTANA.

DESIGN FOR A FAN.

SPECIFICATION forming part of Design No. 26,626, dated February 16, 1897.

Application filed September 9, 1896. Serial No. 605,337. Term of patent 3½ years.

To all whom it may concern:

Be it known that I, JAMES M. RECTOR, a citizen of the United States, residing at Elk Park, in the county of Jefferson and State of Montana, have invented and produced a new and original Design for Fans, of which the following is a specification, reference being had to the accompanying drawing, which forms a part thereof.

10 The drawing forming part of this specification is a plan view of one side of my design, but one view being deemed necessary to fully illustrate the same.

15 The leading features of my design consist in a circular fan A, on which is formed on the upper side thereof, and has at equal distances from the central arm, two circular figures B and C, on which are placed images which represent the candidates of the Democratic party

20 for the presidency at the present time, and

arranged in two circles on the piece A are sixteen circular figures D, and within the central circle and at the center of the fan A is a small circular figure R, and the circular fan A is also provided at its lower side or at the 25 side thereof opposite the figures or images of the candidates with a handle F.

Having fully described my new and original design for the fan, I claim and desire to secure by Letters Patent—

30 The design for a fan as herein shown and described.

In testimony that I claim the foregoing as my invention I have signed my name, in presence of the subscribing witnesses, this 24th 35 day of August, 1896.

JAMES M. RECTOR.

Witnesses:
